Fig. 2.

Fig. 3.

Fig. 4.

FIG. 1 is a perspective view of an electrical switch housing embodying the new design;

FIG. 2 is a side view;

FIG. 3 is a top view;

FIG. 4 is a front view.

The rear of the electrical switch housing is substantially planar and unornamented, said housing may include an electrical connection structure on the back thereof, which structure is obscured from view when the switch housing is mounted, such electrical connection structure does not form a part of the claimed design.

I claim:

The ornamental design for an electrical switch housing, as shown and described.
